UNITED STATES PATENT OFFICE

146,023

DESIGN FOR AN IRONING MACHINE

Charles J. Godfrey, Philadelphia, Pa., assignor to
Horton Manufacturing Company, Fort Wayne,
Ind.

Application December 15, 1945, Serial No. 124,765

Term of patent 7 years

(Cl. D49—1)

To all whom it may concern:

Be it known that I, Charles J. Godfrey, a citizen of the United States, residing at Philadelphia, in the county of Philadelphia, State of Pennsylvania, have invented a new, original, and ornamental Design for an Ironing Machine, of which the following is a specification, reference being had to the accompanying drawings, forming a part thereof, wherein—

Fig. 1 is a front elevational view of an ironing machine showing my new design;

Fig. 2 is a top plan view thereof; and
Fig. 3 is an end elevational view thereof.

The dominant features of my design reside in the portions shown in solid lines.

I claim:

The ornamental design for an ironing machine, as shown and described.

CHARLES J. GODFREY.
